UNITED STATES PATENT OFFICE.

ALLEN E. OSTRANDER, OF RIDGEWOOD, NEW JERSEY, ASSIGNOR TO AMERICAN CAR AND FOUNDRY COMPANY, OF NEW YORK, N. Y., A CORPORATION OF NEW JERSEY.

GENERAL-SERVICE CAR.

1,354,915.

Specification of Letters Patent.

Patented Oct. 5, 1920.

Application filed October 2, 1918. Serial No. 256,536.

To all whom it may concern:

Be it known that I, ALLEN E. OSTRANDER, residing at Ridgewood, Bergen county, State of New Jersey, and being a citizen of the United States, have invented certain new and useful Improvements in a General-Service Car, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

20 In said drawings:

Figure 1 is a top plan of a portion of the car;

Fig. 2 is a two-part longitudinal sectional view of a portion of the car showing the underframing;

Fig. 3 is a two-part vertical sectional view looking toward the movable end wall;

Fig. 4 is a detail sectional view showing the hinged door and a door stop;

30 Fig. 5 is an end elevation of one end of the car;

Fig. 6 is a sectional view taken on the line 6—6 of Fig. 2;

Fig. 7 is a side elevation of a portion of the car;

Fig. 8 is an end elevation of part of the car showing the movable end wall;

Fig. 9 is a sectional view taken on the line 9—9 of Fig. 8;

40 Fig. 10 is a sectional view taken on the line 10—10 of Fig. 8; and

Fig. 11 is a top plan detail view showing the corner post cap and a part of the movable end wall.

45 This invention relates to car construction and more particularly to the type of car that may be employed in general service in the transportation of commodities, either in bulk or packaged, wherein steel center sills 50 are utilized for carrying the major portion of the lading with side and end walls formed of composite material for carrying the remainder of the lading. And, further employing doors, forming a part of the in- 55 cavated bottom wall or floor, that are hing-

edly connected to the center sill construction and extend upwardly and outwardly therefrom to the side sills and walls to which their free ends may be operatively connected by suitable means serving to control their movements both in retaining and discharging the lading from the interior of the car.

By providing a construction wherein the central portion of the bottom wall or floor 65 is incavated so that the top of the center sill lies in a plane lower than the side sills, or the juncture of the side walls with the bottom wall, the lading, due to the downward and inward slope of the floor, tends to 70 gravitate toward the center sill which places the center of gravity relatively low and immediately above the center sill. The bottom wall or floor adjacent the car ends being composite and substantially flat produces a desirable construction and also permits the employment of lading thereon to 75 resist buffing stresses. To further increase the resistance, the end sills of the frame are angularly braced and connected with the 80 side sills and to the draft sills in such a manner that buffing shocks are more or less subdivided in their transmission to the underframe.

One of the end walls may be arranged to 85 be dropped inward, and for this purpose it is loosely connected with a hinge connection to the underframe or end sill. If desired, the loose connection will permit the end wall to be moved without disturbing or utilizing the hinge connection. Suitable stops are also provided to coöperate with the wall as well as a latching device to retain the wall in its vertical position to close the end of the car.

90 To facilitate the discharge of the lading, certain of the transverse members are provided with depending flanges having door stops thereon, which flanges may serve as chutes to direct the lading to one side of 100 the trackway and car.

95 Composite side walls are employed, and by means of suitable trusses formed of U-shaped stakes and braces secured thereto and to the side sills and the ends of the 105 transverse members, the side walls are stiffened to carry their share of the lading. The braces being inclined, coöperate with the stakes and side walls to produce a trussed side wall structure.

In the embodiment illustrated, the under-frame comprises a center sill construction composed of spaced channel members A and B having webs 1 and 2 of substantially uniform depth. The web 1 of the member A is provided with outturned flanges 3 and 4 constituting the compression and tension flanges. The web 2 of the member B is similarly provided with outturned flanges 5 and 6.

The bolsters C and D, shown in Figs. 1 and 2, are pierced to permit the passage of the channel members A and B therethrough. At suitable intervals the members 15 A and B are spaced and braced by suitable pan-shaped members indicated at 7 and 8.

The bolsters C and D are preferably formed of pressed diaphragms 1^a, center fillers 1^b with top and bottom cover plates 20 1^c and 1^d, respectively, and are provided with the usual center and side bearings. Outwardly from the bolsters, the center sill members A and B may be arranged to receive suitable draft gear E, as shown in 25 Fig. 6. Near the outer ends of the sill webs 1 and 2 are draft lugs 10 and 11 that serve as stops or abutments for the draft gear. In Figs. 2 and 6, the end portions of the sill members serve as draft sills, but the 30 draft sills may be of separate construction and secured to the ends of the center sills. To support the draft gear E, a bracket 10^a 35 may be employed which also serves as a bracing and spacing element for the members A and B of the center sills.

The end sills F and G may each be formed of pressed steel and have relatively deep diaphragms 12 and 13 that in turn are provided with inturned flanges. The flanges 40 for the sill F being indicated at 14, 15, 16 and 17 in Figs. 2 and 6, while the corresponding flanges for sill G are indicated at 18, 19, 20 and 21 in Fig. 5. As shown the top flanges 14 and 18 are wider than the 45 bottom flanges 15 and 19. This provides a better bracing for the end and also serves as a plate for supporting the wood flooring sections H and I which extend horizontally across the end of the car. Fig. 6 shows to 50 better advantage the general arrangement of the flooring sections. To further support and brace the flanges 14 and 18 suitable pressings are employed to fill the space between the top of the center sill and the 55 flanges. One of these is shown at 22 in Fig. 6. This figure also shows a flanged supporting element 23 extending outwardly beneath the flooring H and secured to the cover plate 24 of the center sill construction. This element also serves as the top 60 cover plate of the bolster D, and, as shown, is approximately Z-shaped in cross-section. The floor sections may be composed of strips of wood placed transversely of the car and

provided with rabbets on their longitudinal edges as shown in Fig. 6.

The cross bearers indicated at J and K in Figs. 1 and 2 are in the form of pressed flanged diaphragms, and to produce an excavated bottom wall or floor, they are tapered and inclined upwardly and outwardly from the center sill construction. These cross bearers are reinforced by strips 25 secured to top flanges of the diaphragms and extending substantially across the 75 width of the car. The outer ends of these strips are so bent upwardly as to form a recess between them and the upper flanges of the cross bearers for receiving one flange of each of the angle side sill members 26 80 and 27 as shown in Fig. 3.

Between each of the cross bearers, the center sill construction and a side sill there is formed a door opening indicated at L. The projecting edges of the center sill top 85 plate 24 and the strips 25 form striking plates to engage with a door 28. In order to provide for swinging the doors, door brackets 29 are connected to the sills, as shown in Fig. 4. This bracket is perforated 90 for the door pintle 30 coöperating with the butt strap 31 secured to the door. By this arrangement a hinge connection is formed below and to one side of the door and is further protected by the projecting edge 95 of the top plate 24. To limit the downward movement of the door 28, the cross bearer is provided with a door stop 32 secured to a flanged member 33 secured to the lower flanges of the cross bearer K.

100

Fig. 4 shows a portion of this member 33 projecting downwardly from and angularly to the cross bearer to form chute sides 33^a to coöperate with the door. The door stop 32 is preferably secured to the outer and 105 lower corner of the part 33^a of the member 33. The size and projection of the parts 33^a of the member 33 may be varied to form more or less of a chute and the door stop 32 may have its position varied relative to 110 the member to conform to other desired discharging conditions.

Near the outer ends of certain of the cross bearers, brackets 34 are secured to the diaphragms thereof through which brackets 115 may pass suitable operating shafts for any usual type of door operating device (not shown.)

Secured to the flanged ends of the cross bearers are flanged U-shaped side stakes 120 35 which are secured also to the vertical standing flanges of the side sills 26 and 27. In this connection it should be noted that these flanges are in alignment with the flanges at the ends of the cross bearers. To 125 provide seats for the horizontally arranged flanges of the side sills, the upper sides near the ends of the cross bearers extend hori-

zontally as shown in Fig. 3. To protect these flanges and also to provide stops for the doors 28, striking strips 36 are secured on the horizontal flanges of the side sills.

5 The end sills F and G are provided with suitable buffering devices 37 that may be of any conventional type. These devices, as shown in Figs. 2 and 5, are spaced from each other, and to provide for a better distribution of buffering shocks, suitable braces are employed to subdivide and transmit those shocks. In Fig. 2 it will be seen that two angularly arranged channeled braces are utilized to the rear of the buffering device 37.

10 15 One of the braces 38 extends from its point of securement to the side sill and end of the bolster to its attachment with the diaphragm of the end sill. To provide for this attachment the end of the brace is bent, as shown. The companion brace 39 extends from its point of attachment with the center sill member forward of the bolster to its point of securement to the end sill diaphragm. The end of this brace is also angularly bent, as shown. An inspection of Fig. 2 shows that the buffer head is at approximately the apex of the triangle formed by the braces 38 and 39. By this arrangement of bracing it is evident that buffering shocks are subdivided and transmitted to the under-frame including the side sills and the center sill construction without strain in the separate sills.

20 25 30 35

Patent No. 2,000,000
Date Sept. 2, 1935
Further, Fig. 2 shows that the ends of
35 channelled members comprising the center
sill construction are connected to the dia-
phragm 12 by means of the angles 40 and
41. An additional brace or floor support 42
extends longitudinally rearward from the
40 top flange 14 of the end sill F and has its
other end secured to the underside of the
top cover plate 1^c of the bolster D. Four
of these braces are employed but only one
is shown and that in Fig. 2. This figure
45 shows that it is slightly off-set from the axis
of the buffing device 37. To prevent the
braces 38 and 39 from spreading, a flanged
tie plate 43 is secured near their outer bent
ends. This tie plate has a horizontal web
50 and vertical flanges connected to the braces
38 and 39 (see Fig. 2).

Mounted on the side sills 26 and 27 are furring strips 44 one of which is shown in Fig. 3. These strips are approximately triangular in cross section and serve to provide ⁵⁵ shedding surfaces for the lading.

The sides of the car are of composite construction, that is wood boards 45 are employed in conjunction with the U-shaped vertically disposed stakes 35. These boards 60 45 and the stakes 35 are secured together and to form trussed side walls suitably inclined or diagonally placed braces are employed. Certain of the braces are wide as indicated at 46, while others are slightly less 65 in width as indicated at 47. The posts and

diagonal braces are connected with the boards and gusset plates 48 to connect the end of the braces with the flanges of the stakes. As shown in Fig. 7, there is a plate at each end of the brace 46. The lower plate 48 serves to connect the flange of the stake and brace to the side sill. 70

The top edges of the sides of the car are provided with the compression angles 49 and 50 which serve to stiffen the sides and to form the top chord of the truss. The uppermost boards 45 are rabbeted on one side to form a seat for each vertical flange of the members 49 and 50. 75

The upper plate 48 ties the upper end of 80 the brace 46 and the wood strips or boards with a flange of a stake 35 and the vertical flange of one of the compression angles as shown in Fig. 7. The braces 46 and 47 are preferably formed of flat stock, while a 85 brace 51 is formed as an angle. The braces 51 are connected to the angle members 49 and 50, to the wood strips 45, and to the gusset plate 20^a extending rearwardly from the end sill. To provide for this attachment to the plate 20^a, the lower end of the braces are bent to lie in a vertical plane as 90 shown.

One end wall of the car is preferably solid or immovable and is composed of wood strips 52 and the U-shaped end stakes 53. The stakes are provided with outturned flanges so as to provide a flat securing surface and are formed similarly to the side stakes 35. As shown, this immovable end wall is provided with two stakes whose lower portions are secured to the outer face of the web or diaphragm 13 of the end sill G. To connect the strips 52 with the strips 45, suitable corner posts 54 and 55 are employed. These posts may be formed of rolled or pressed angles and extend upwardly from the corners of the end sill G to which they are connected. Suitable means are employed to secure the wood strips 45 and 52 to the posts, which means may be the bolts 56, as shown. 110

The top edge of the immovable end wall is provided with an angle member 57 having one of its flanges lying horizontally. Extending across the upper end of this wall and connected to the members 49 and 50 are planks 58 which serve as a spacing member and also for bracing the side walls.

The other end wall is movable, and is formed of wood strips 59 while its ends are provided with angle protecting members 60 and 61. The upper edge of the wall is provided with an angle member 62 and the vertical flange thereof is secured on the inner face or side of the wall so that the horizontal flange forms a protecting edge. 125

At spaced intervals, the lower edge of the wall is notched as indicated at 63 in Figs. 3, 8, 9 and 10. To cover these notches or openings 63, the cover plates 64 and 65 are 130

employed. Each of these plates is provided with an opening. To further retain the wood strips 59 in position, the straps 66 and 67 are secured upon each side thereof. Each 5 of these straps is U-shaped with limbs of different lengths, the shorter one being on the inner side of the wall. When these straps are in position, the limbs pass through the openings in the plates 64 and 65 and a 10 curved end closed slot or loop is formed by the lower end of the strap for disposal in the notch 63. To coöperate with the loop so formed, a link 68 is loosely connected therewith. This link is shown as having 15 the shape of a trapezium and formed of round stock, with its configuration generally resembling the notch 63 in which it is operatively placed.

The link 68 is rotatably mounted in spaced 20 bearings formed by the eye bolts 69. These bolts have a square shoulder formed just below the eye so that they will have a relatively large contacting area with the angle member 70 which serves as a stop or abutment for the lower edge of the wall. The 25 shanks of the eye bolts pass through suitable holes in a flange of the angle 70, through the wood flooring and are connected to the car underframe as for example to the 30 upper flange 14 of the end sill, which bolts then serve to securely hold them together.

The lower edge of the end wall is adapted to contact with the vertically arranged flange 71 of angle 70 and the outward movement of the end wall is thus prevented by 35 this latter flange. As shown more particularly in Fig. 10, the eyes of the bolts 69 lie between the plates 64 and 65 when the end wall is in a vertical or closed position. 40 It will also be seen that each link 68 is approximately vertical and is protected against injury by the plates 64 and 65, the flange 71 and the straps 66 or 67. Thus the end wall, link and eye bolts lie in substantially 45 the same vertical plane.

The movable end wall is provided with the wear strips 73. If desired a protection angle 74 may be secured to the inner side and bottom edge of the wall or end door.

50 Each of the corner posts at this end of the car is provided with an abutment formed of an angular pressing 75. This will provide two flanges in a vertical direction one of which is secured to the side wall while 55 the other flange projects transversely and partly across the end, a filler strip 72 being secured to the inner edge portion of the pressing as shown in Fig. 8. The lower portions of one of these angle pressings are 60 secured to the diaphragm 12 and to the flange 17 of the end sill, and the other abutment has its flanges secured to the diaphragm 12 and to the flange 16.

The flange 75^a which forms a stop for the 65 end wall, has a tapered or inclined edge so

that the flange is wider at the bottom than at the top. Mounted on each of the corner posts is a cap 76 which is a flanged gusset so arranged that one of its flanges is secured to the flange 75^a of the member 75 and its other flange to the horizontally positioned flange of the angle forming the top chord of the composite side wall, which member may be 49 or 50, thus additionally securing said pressing to assist it in resisting end thrust 75 of the end door.

To hold the end wall in a closed position, suitable latching devices may be employed, and one form comprises a plate 77 secured to the wall with a link 77^a formed as an eye 80 bolt mounted at one end. A latch 78 is movably connected to the link and is adapted to engage with a catch 79 secured on the flange 75^a.

From the above description it will be seen 85 that a car is provided with longitudinal sills and cross bearers so arranged that an incavitated bottom wall or floor is formed to extend over a large portion of the car. The end portions of the floor are formed of wood 90 strips arranged to produce a flat and horizontal lading platform to coöperate with the remainder of the bottom wall. Lading may be readily discharged by means of the hinged bottom doors, and should it be desired to carry material that may be more conveniently loaded and discharged from one end, one end wall is made movable.

The movable end wall is so arranged that it may be moved without bringing into play 100 the actual hinge connection as the slot formed at the end of the strap permits vertical and other movements without rotating the link in its bearings. By the novel arrangement of the several elements, it is manifest that the loose connection and hinged mounting are protected at all times from injury by the lading. Again, when the end wall is raised to a vertical position the several elements are self-contained or inclosed 110 and are also in substantially vertical alignment and thus there are no protruding parts. The end wall is held against outward movement by means of the stops 71, 73^a and 76.

It is evident that the construction herein 115 described and illustrated in the accompanying drawings provides a drop end gate adapted for use in a gondola or general service car with a hinge or hinges so constructed and arranged as to take up some of the 120 stresses on the gate, thereby preventing the bulging of the gate and the consequent tendency of the car to leak due to pressure of the lading.

What I claim is:

1. A car construction comprising a flanged 125 end sill, side walls, angular abutments secured to said end sill web, end sill flanges and side walls, an end wall pivoted to an end sill flange and engaging said abutments and 130

a flanged member secured to said end sill and caps secured to said abutments for engaging said end wall.

2. A car construction comprising longitudinal and end sills, composite side walls having a trussed form, a loosely connected and hingedly mounted drop end, transverse members inclined upwardly from the center sill, doors hingedly connected to said center sill and to operate between said center sill, a side sill and a pair of transverse members and forming therewith an incavated bottom wall, the bottom wall of said car near one end being substantially flat, and means for retaining the drop end in a vertical and closed position.

3. A car construction having an underframe comprising longitudinal and end sills, transverse members, an incavated bottom wall having a plurality of openings therein between said members, doors for said openings, a portion of said bottom wall adjacent one end being flat, trussed side walls and end walls, one of said ends being loosely connected with said underframe.

4. A car construction comprising longitudinal and end sills and transverse members, an incavated bottom wall forming part of the floor and having a plurality of openings therein, said wall being inclined downwardly from the side sills to the center sill, doors for said openings, the end of the floor adjacent one end sill being substantially flat, trussed side walls, end walls, one of said ends being loosely connected with an end sill of said underframe, and means to retain said end in a closed position.

5. A car construction having an underframe comprising longitudinal and end sills and transverse members, an incavated bottom wall having a plurality of openings therein, doors for the openings, a portion of said bottom wall at one end thereof being substantially flat, trussed side walls, end walls, one of said ends having a loose connection with said underframe through a hinge mounting.

6. A car construction comprising a center sill construction, composite side and end walls, transverse members inclined upwardly from said center sill and attached to said side walls, and a bottom wall, a part of which is composed of a series of doors operating in either direction through and beyond a horizontal plane, and another part of said bottom wall at one end of the car being substantially flat.

7. A car construction comprising trussed side walls, end walls, a center sill construction, and a bottom wall incavated for a portion of its length and horizontal at said center sill construction and at its ends.

8. A car body having a bottom wall and comprising fixed flat end portions and an incavated central portion, a series of down-

wardly and inwardly inclined doors and a center sill construction having a horizontal top plate forming the longitudinal central portion of the incavated central portion.

9. A car body having a bottom wall comprising horizontal end portions and an incavated central portion, trussed side walls and end walls, one of said end walls being loosely and hingedly mounted, a series of drop doors and a center sill construction having a horizontal top plate forming the longitudinal central portion of the incavated central portion.

10. A car construction comprising a center sill construction, side and end walls, said side walls having stakes and inclined braces therebetween to form a truss, one of said end walls being loosely connected and hingedly mounted, and an incavated bottom wall provided with end portions lying in a horizontal plane.

11. A car construction comprising a center sill, a bottom wall incavated for a portion of its length and horizontal at said center sill and at an end and a pivoted end wall adapted to fold back upon said horizontal end portion.

12. A car construction comprising a center sill, a bottom wall incavated for a portion of its length and horizontal at said center sill and at an end, side walls, abutments carried by said side walls and a pivoted end wall adapted to engage said abutments and said horizontal end portion.

13. A car construction comprising a center sill, a bottom wall incavated for a portion of its length and horizontal at said center sill and at an end, an end sill, an end wall pivoted to said end sill and adapted to fold back upon said horizontal end portion.

14. A car construction comprising a center sill, a bottom wall incavated for a portion of its length and horizontal at said center sill and at an end, side walls, abutments carried by said side walls, an end sill, and an end wall pivoted to said end sill and adapted to engage said abutments and said horizontal end portion.

15. A car construction comprising a flanged end sill, side walls, angular abutments secured to said end sill web, end sill flanges and side walls, an end wall pivoted to an end sill flange and engaging said abutments.

16. A drop end wall for a car having an underframe including an end sill, elongated U-shaped straps secured to the end wall and forming slots at their lower ends, links loosely connected to the slots to allow vertical movement of the end wall independently of the position of the links, a flanged member secured transversely of the car above the end sill to form a stop for the end wall and eye-bolts passing through the stop and the end sill rotatably mounting the links.

17. A car construction comprising a drop end wall, spaced posts adjacent said wall, caps for the upper ends of said posts, said caps being provided with flanges to serve as stops for the end wall, an end sill, a stop thereon, a U-shaped strap secured to said end wall and forming a vertically disposed loop at its lower end, a link loosely connected with the loop, and eye-bolts removably securing the stop to the end sill and providing a hinge connection with the link, said loop permitting end wall movement independently of the hinge connection. 40
18. A drop end wall construction for a car having an end sill comprising an end wall having spaced notches formed in its lower edge, a U-shaped strap having a limb secured upon each side of the wall and forming a loop in a notch, a link loosely connected with the loop and movable in a notch, and an eye-bolt passing through the end sill of the car and having a hinge connection with another portion of the link. 45
19. A drop end wall connection for a car having an underframe, which comprises an end wall having spaced notches formed in its lower edge, perforated plates secured upon each face of the wall and covering said notches, a U-shaped strap having its limbs passing through a perforation in each plate with its transverse portion lying in the notch between the plates, the limbs being secured upon opposite faces of the wall, a link loosely connected with the strap between said plates, a plurality of vertically posi- 50
- tioned eye-bolts secured to an end sill with their eyes disposed to lie in the notch and to have a rotatable connection with the link, and a stop secured on the end sill adapted to engage the lower edge of said wall. 55
20. A car end construction comprising an end sill, standards rising therefrom and defining the sides of an endgate pocket framing, a member spaced from the end sill and forming a base for said framing, flooring between said base member and sill, and an end gate disposed within said framing. 60
21. A car comprising an underframe, a drop end wall, elongated U-shaped straps secured to said end wall, eye bolts secured to said underframe, links connecting said eye bolts and straps and permitting vertical movement of said end wall, supports carried by said underframe and engaged by said end wall and caps on said supports limiting the vertical movement of said end wall. 65
22. A car end comprising a flanged end sill, side walls, standards secured to said end sill and side walls and defining the sides of an endgate pocket framing, a member spaced from the end sill and forming the base for said framing, flooring between said base member and sill, an endgate disposed within said framing and means pivotally connecting said endgate and said sill and securing said base member to said sill. 70

In witness whereof I have hereunto set my hand.

ALLEN E. OSTRANDER.
